United States Patent Office.

GEORGE R. MOORE, OF PHILADELPHIA, PENNSYLVANIA

Letters Patent No. 91,761, dated June 22, 1869.

IMPROVEMENT IN LEVERS FOR OPERATING WATER-CLOSET PANS AND VALVES.

The Schedule referred to in these Letters Patent and making part of the same.

To all whom it may concern :

Be it known that I, GEORGE R. MOORE, of the city and county of Philadelphia, in the State of Pennsylvania, have invented certain new and useful Improvements in Water-Closet Levers for Pan and Valve; and I do hereby declare that the following is a full and exact description thereof, reference being had to the accompanying drawings, and to the letters of reference marked thereon.

The object of my invention is to provide an improved adjustable pull-lever, or lever connecting with the rod and knob, commonly called the pull, for operating the pan and the valve used in and upon the hoppers of water-closets.

Figure 1 is a side elevation of the lever A A, a branch, B, which operates the valve in the usual way, pull-rod C, knob D, pivoted nut E, bolt and axle F, and eccentric, G, which connects at b with a lever, to operate the pan in the usual way.

Figure 2 is a plan or top view of the same.

Figure 3 is a top view of the removable section of A A.

Figure 4 shows how the pull-rod C connects with the pivoted nut E.

Figure 5 is a plan view of the pivoted nut E.

The holes a a a in the lever are optional bearings

for the nut E. The bissections of the lever A A are held together by the ordinary bolt F, used in closet-levers, and have one end extending through the eccentric G, for an axle to the same. The square b, in the eccentric, is fastened to a lever, which holds and operates the pan, all in the usual manner.

By unscrewing the nut H upon the bolt F, the sections of the lever may be parted, and the pivoted nut E moved to any of its several bearings a a a, by which the pull is brought more or less remote from the axis of the lever; also, the pull-rod C may be screwed, at pleasure, through the nut E, and thus all the desired adjustability of the pull to the lever is cheaply and conveniently obtained.

What I claim as my invention, and desire to secure by Letters Patent, is—

1. The lever A A, constructed substantially in the manner and for the purpose herein set forth.
2. The pivoted nut E, combined with the lever A A and the pull-rod C, substantially in the manner and for the purposes herein set forth.

GEO. R. MOORE.
